(57) **CLAIM**

The ornamental design for an art frame, as shown and described.

DESCRIPTION

FIG. 1 is a front perspective view of an art frame, showing my new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof; and,

FIG. 8 is a rear perspective view thereof.

The broken lines showing artwork in FIG. 1 and a cardboard stand in FIG. 8 are included for the purpose of illustrating the invention in use, and form no part of the claimed design.
